UNITED STATES PATENT OFFICE.

JAMES Y. HUGHES, OF QUANAH, TEXAS.

COTTON-SEPARATOR.

1,153,180.

Specification of Letters Patent. Patented Sept. 7, 1915.

Application filed May 3, 1910, Serial No. 559,075. Renewed August 2, 1915. Serial No. 43,347.

To all whom it may concern:

Be it known that I, JAMES Y. HUGHES, a citizen of the United States, residing at Quanah, in the county of Hardeman and State of Texas, have invented new and useful Improvements in Cotton-Separators, of which the following is a specification.

My invention relates to apparatus for cleaning seed cotton and separating the dust 10 and dirt therefrom prior to the ginning operation.

Prior to my invention, there have been devices manufactured for the purpose of cleaning seed cotton, in some of which revolving 15 screens or sieves have been used to separate the dust in connection with revolving blades or blower attachments.

It is my purpose to improve upon all such prior devices with which I am aware, and 20 to overcome the difficulties which have been encountered in using such cotton separators.

My invention will be better understood from the following description in connection with the accompanying drawings, in 25 which—

Figure 1 is a vertical cross-section of an apparatus embodying my invention; and Fig. 2 is a longitudinal section on the line II-II of Fig. 1.

The cleaning apparatus comprises a main 30 casing 1, divided by a vertical partition 2 having a plane unobstructed front face into two compartments, 3 and 4. A seed-cotton conveyer-flue 6, leads into the cotton separator compartment 3, and an exhaust or suction pipe 7, in alinement with the flue 6, leads from the opposite wall of the dust compartment 4 and is connected to a suitable blower or suction-pump. The lower 35 part of compartment 3 terminates in a chute 8, preferably located directly over the belt-distributer 9, which conveys the cotton to the discharge hoppers 10 and 11, of the cotton gins. The compartment 4 has a closed 40 bottom 12, which is preferably hinged as shown, for the removal of any dirt that may accumulate therein.

Revolutely mounted in a circular aperture in the partition 2, is a perforated separating 45 wheel 14 having a plane unobstructed operating face, which may be rotated in any suitable manner, as by gearing connected with a shaft of the belt-distributer as shown in Fig. 1. It will be observed that the upper 50 portion of this reticulated wheel is a direct line between the conveyer-flue 6, and the suc-

tion-pipe 7, so that there will be a strong air-blast across the top portion of the wheel, while the lower portion will move in a practically dead-air-space. The result of this 60 arrangement is to cause the seed-cotton forced through the conveyer-flue 6, to strike against the upper part of the revolving perforated wheel and to be held there by the strong suction from the pipe 7 directly opposite. The strong air-blast against the cotton as it is suddenly arrested against the 65 perforated wheel will effectually drive out the dust and dirt, most of which will be carried through the chamber 4 and into the 70 suction-pipe 7 with the exhaust, some of the heavier particles falling down into the dead-space in the bottom of the chamber. As the wheel 14 revolves, the cotton adheres to it until it is carried down into the lower portion 75 of chamber 3, where there is practically no suction, the cotton being there thrown off by centrifugal force and gravity upon the distributing belt 9.

The construction and arrangement of my 80 separator wheel have a number of decided advantages over the prior devices. In such devices with which I am familiar, the separator, whether stationary or revoluble, consists of a wire sieve, which causes great 85 difficulty by reason of the wire meshes becoming clogged, the cotton entering the interstices and clinging tenaciously thereto. I have overcome this difficulty by employing a perforated metal disk or wheel, having a 90 reticulated plane smooth surface from which the cotton readily slides off as soon as the suction ceases.

For the purpose of overcoming some of the difficulties encountered in the use of 95 screens of wire-mesh, it has been proposed to provide the revoluble separator with vanes or blades. These, however, interfere with the free circulation of air in front of the separator wheel, which I have found to be 100 essential, and also cause some injury to the cotton fiber by their impact. On the other hand, the smooth plane surface of my separator wheel causes no injury whatever to the cotton, and the entire surface is freely 105 exposed and unobstructed. I wish also to call attention to another important advantage possessed by my arrangement. It will be observed that the separator wheel is in the plane of movement of the distributer 110 belt and that adjacent portions of the wheel and belt revolve in the same direction, so

that the cotton is given an initial movement in the direction of movement of the belt as it is thrown off the wheel. There is, therefore, less liability of any injury to the cotton as it falls upon the moving belt. These several features which result in the easier handling of the cotton, by which there is less liability to injury of the fibers, will be appreciated as very important by cotton-ginners and others familiar with this art.

If, at any time, the suction in the pipe 7 should be too great, this will be automatically relieved by a valve 19, which may be connected in the top or side walls of the chamber 4.

The operation of the separator may be inspected through the glazed sights 18.

In operation the seed-cotton is carried through the conveyer-flue 6, and is arrested by striking the upper portion of the separator wheel 14, the dust and dirt being drawn through the perforations and carried away in the suction-tube 7, the cotton being carried downwardly by the revolving wheel until out of the air-blast when it is thrown downwardly and in the direction of the moving distributer belt 9, by which it is carried to the bins 10, 11, leading to the gins. Inasmuch as the suction for the air-blast is derived entirely from an outside source connected to the pipe 7, the separator wheel 14 may be revolved comparatively slowly. Furthermore, as the chute 8 is arranged longitudinally of the distributer belt, it may have a large capacity and be capable of handling cotton for a number of gins.

In addition to the several important features which have been previously pointed out, other advantages of my separator will be apparent to those familiar with cotton machinery.

While I have described somewhat in detail the apparatus disclosed in the drawings, it will be evident to those skilled in this art that changes may be made therein without departing from the spirit of my invention or the scope of my claims, which are—

1. A cotton separator comprising a casing divided by a partition into two chambers, a perforated separator-wheel having a substantially plane unobstructed smooth operating surface and revoluble within an opening in said partition and in the plane thereof, one of said chambers having an opening for a conveyer-flue in its side wall and terminating at the bottom in a chute,

the other chamber having an opening in its wall for a suction-tube and having its bottom portion closed to form a dust receptacle, and means for operating said separator-wheel.

2. In combination, a cotton separator comprising a casing having opposite walls connected respectively to a conveyer-flue and to a suction-tube, a perforated separator-wheel revoluble within said casing having a plane unobstructed operating surface and having its upper portion in alinement with said flue and tube, said casing terminating at the bottom in a chute, and a distributer belt co-operating with said chute and arranged to move in the plane of said separator-wheel and in the same direction as the adjacent portion thereof.

3. A cotton separator comprising a casing divided by a partition into two chambers, said partition having an opening therein, a conveyer flue entering the wall of one chamber and a suction tube entering the wall of the other chamber, said tubes being in alinement, a rotary screen having a plane unobstructed face operating within said opening and in alinement with said partition, said rotary screen being controlled independently of the blast supply, a distributer located beneath said casing and arranged to move in the plane of the screen, and adapted to receive the cotton when thrown from the screen, said screen and distributer being operated by a common source of power whereby a constant and uniform relative speed is secured between the two.

4. A cotton separator, comprising a casing divided by a partition into two chambers, a perforated separator-wheel having a substantially plane unobstructed smooth operating surface and revoluble within an opening in said partition, one of said chambers having an opening for a conveyer-flue in its side wall and terminating at the bottom in a chute, and the other chamber having an opening in its wall for a suction-tube, and means for operating said separator-wheel.

In testimony whereof I have hereunto set my hand in presence of two subscribing witnesses.

JAMES Y. HUGHES.
